The ornamental design for a lid, as shown and described.

DESCRIPTION

FIG. 1 is a front perspective view from above of a lid over a container showing my new design;

FIG. 2 is a right side view thereof, identical to a left side, a front, and a back view;

FIG. 3 is a top view thereof;

FIG. 4 is a bottom view thereof;

FIG. 5 is a perspective view from above with a right side flap in a locked position; and,

FIG. 6 is a bottom view of the lid without the container. Broken lines in FIGS. 1, 2, 4, and 5 are for the purpose of illustrating the lid in use, and form no part of the claimed design.
